UNITED STATES PATENT OFFICE

MICHAEL J. TRACY, OF ST. LOUIS COUNTY, MISSOURI

FLOOR CONSTRUCTION

Application filed March 14, 1930. Serial No. 435,690.

This invention relates to floor construction, and has special reference to floors comprising solidified plastic material, such as concrete.

3 An object of the invention is to provide an improved construction for supporting floors made of concrete and the like, and also to provide improved means for covering the corners formed by the intersections of the 10 floors with the walls and partitions of the building, so as to prevent the accumulation and deposit of moisture and dirt and other substances in and along the corners and to provide curved members covering the corners and forming smooth surfaces from which the moisture and dirt and other substances may readily be removed.

Another object of the invention is to provide an improved construction for supporting floors and covering the corners formed by the intersection of the floors with the walls and partitions of the building to prevent water and foreign substances from becoming lodged in the corners. By my improved construction, the cleaning of the floors along the edges thereof and at the intersection of the floors with the walls and partitions of the building, and also the cleaning of the ceilings at such intersections 25 with the walls and partitions of the building, is greatly facilitated, thus improving the sanitary conditions and also contributing to the desirability of this invention.

Other objects will appear from the following description, reference being made to the accompanying drawings, in which—

Fig. 1 is a vertical sectional view showing one embodiment of the invention.

Fig. 2 is a vertical sectional view showing a different form of supports for the floors.

Fig. 3 is a vertical sectional view showing still another form of supports for the floors.

Fig. 4 is a perspective view of the floor supporting and corner covering device shown in section in Fig. 1.

Fig. 5 is a perspective view of the corner covering device shown in section in Figs. 2 and 3.

The floors 1 are composed of concrete or other material suitable for this purpose.

The material is laid in a plastic condition and permitted to solidify. The partition 2 may be made of sheet metal or other material as desired.

Along each wall and along the sides of each partition are located the devices which are shaped and formed to cooperate with the walls and partitions and floors to provide rounded corners at the intersection of the floors with the walls and partitions, so as to exclude from such corners water and other substances.

In the embodiment shown in Fig. 1, these devices also cooperate with the undersurfaces of the floors which constitute the ceilings of the rooms below, so as to exclude dirt and other substances from the corners formed by the intersection of the ceilings with the building walls and partitions. If desired, the ceilings may be made wholly or partly of metallic plates 3 having their edges upturned to provide flanges 4.

Along each edge of each floor, a plate 5 is located against the building walls and against the partitions with which the floors cooperate to provide rooms. The concrete extends to contact with the plates 5 above the edges of the flanges 4. The plates 5 are of considerably greater vertical width than the thickness of the floors, so that the upper edges of said plates are considerably above the floors and the lower edges of said plates are considerably below the ceilings formed by the floors. The upper edges of the plates 5 are bent downwardly and curved laterally to provide laterally curving flanges 6 having their upper edges approximately flush with the upper surfaces of the floors. Thus, these flanges 6 form curved or rounded corners covering the joints at the intersection of the floor with the plates 5, and positively preventing the lodgment of dirt and other substances in said corners. The surfaces of the flanges 6 are smooth, so that they may readily be cleaned.

The lower edges of the plates 5 are bent upwardly and laterally to provide laterally curved flanges 7, seating closely against the ceiling 3, whether the said ceiling be formed of a metallic plate or not. Thus the flanges

7 prevent the lodgment of dirt within the joints formed at the intersection of the floors with the walls and partitions of the building, and facilitate the cleaning of the walls and the ceiling.

5 In the construction shown in Fig. 2, an angle bar is placed along each side of the partition 8. The vertical flanges 9 of the angle bars are against the partition 8 and the horizontal flanges 10 of said angle bars extend laterally away from said partition. The ceiling forming plates 11 are seated upon the flanges 10. Upon the ceiling forming plates 11, the concrete or other solidified plastic material is placed and smoothed to provide floors 12. Flanges 10, bearing closely against the sides of the partition 8 and being impervious to moisture, prevent the lodgment of moisture and dirt within the joints or corners. The surfaces of the partition and of the flanges 10 being smooth, no difficulty is encountered in keeping the joints in a clean and sanitary condition.

25 Along each wall and along each side of each partition, a plate 13 has its lower edge extending downwardly between the floor 12 and the wall or partition, and its upper edge projecting substantially above the floor and bent downwardly and curved laterally to provide a rounded corner flange 14. The lower edge of the flange 14 extends into the upper surface of the concrete or floor material, so that the upper side of the flange is flush with the upper surface of the floor. 35 Thus the corners are covered and shielded, preventing the lodgment of dirt therein and facilitating the cleaning of the floors and walls so as to keep the premises in a sanitary condition.

40 In the arrangement shown in Fig. 3, the metallic ceiling is omitted. The partition 15 has its lower edge bent laterally to provide a laterally extending flange 16, the undersurface of which is flush with the undersurface of the floor 17, which forms the ceiling of the room below. At the opposite side of the partition, the floor 18 has its undersurface formed flush with the undersurface of the flange 16 and with the undersurface of the floor 17, so that a continuous smooth ceiling is provided. The floors 17 and 18 may be constructed of concrete or other appropriate material, and the corners formed by the intersection of said floors with the walls and partitions of the building are shielded and covered by curved flanges 19 extending downwardly and laterally from the upper edges of plates 20. The lower edges of the plates 20 are embedded between the building walls and partitions and the floors of the building. The upper edges of the flanges 20 form curved surfaces, beginning smoothly with the upper surfaces 55 of the floors and providing a construction

which may easily be cleaned and kept in a sanitary condition.

It is now clear that my improved floor construction is designed and adapted for use in many types of buildings. It is well adapted for buildings of the institutional type, though it may be used with equal satisfaction in buildings for other purposes, such as store buildings, office buildings, manufacturing establishments, and the like. The construction and arrangement may be varied otherwise than as particularly indicated in the drawings, and I contemplate such variations as may be desirable in the particular embodiments in which the invention is used. I do not restrict myself in any unessential respects, but what I claim and desire to secure by Letters Patent is:—

1. In a building, a wall, a concrete floor, a plate mounted between the floor and the wall and extending above and below the floor, and laterally curved portions rigid with the upper and lower edges of said plate covering the upper and lower marginal portions of said floor adjacent to said wall. 35

2. A building comprising a building wall, a floor extending laterally from said wall, a device of curved form at the juncture of the wall and floor preventing accumulation of substances at said juncture, and a part in connection with said device extending and clamped between the floor and the wall and holding said device rigidly in the position aforesaid. 55

3. In a building, a wall, a floor extending away from the wall, a plate of curved form at the juncture of the wall and floor preventing accumulation of dirt and other substances in the corner formed by said wall and said floor, and a portion integral with 100 said plate and extending downwardly and secured between said wall and said floor and holding said plate rigidly in the position aforesaid. 105

4. In a building, a wall, a floor extending away from said wall, a plate extending upwardly and secured between said floor and said wall, and an upwardly and laterally curved portion in connection with the lower edge of said plate having its edge engaging 110 the underside of said floor and preventing the accumulation of dirt and other substances in the corner formed by said floor and said wall. 115

5. In a building, a wall, a floor extending away from said wall and forming corners at the juncture of the floor and the wall, a plate extending between the floor and the wall and having its upper and lower edges respectively above and below the floor, and 120 curved portions in connection with the upper and lower edges of said plate extending into contact with the upper and lower surfaces of the floor and cooperating with said floor to hold said plate in position and preventing 125

the accumulation of dirt and other substances in corners at the juncture of the floor and wall.

6. In a building, a wall, a floor extending away from the wall, and a metallic plate having a portion engaged between the floor and the wall and having a downwardly and laterally curved portion on its upper edge extending downwardly and laterally into the upper surface of the floor and preventing the accumulation of dirt and other substances at the juncture of the floor and wall.
